UNITED STATES PATENT OFFICE.

WILLIAM TOMLINSON, OF ST. CATHERINES, ONTARIO, CANADA.

RAILROAD-TIE.

1,345,287.

Specification of Letters Patent. Patented June 29, 1920.

Application filed November 9, 1918. Serial No. 261,815.

To all whom it may concern:

Be it known that I, WILLIAM TOMLINSON, a subject of the King of England, residing at St. Catherines, in the Province of Ontario and Dominion of Canada, have invented new and useful Improvements in Railroad-Ties, of which the following is a specification.

The invention is designed to provide a new and improved form of railroad tie formed with a steel outer covering and a concrete interior whereby the most effective construction for strength and length of service is obtained. It is further designed to provide a device of this character in which unique means is provided for the attachment of the rails to the tie.

To the exact construction in which it is shown and described, the invention is not to be restricted. The right is reserved to make such changes or alterations as the actual reduction to practice may suggest, in so far as such changes or alterations are comprehended in spirit by the annexed claim.

25 In the accompanying drawings:

Figure 1 is a top plan view of the tie, sections of track rails being shown attached thereto.

Fig. 2 is a bottom plan view.

30 Fig. 3 is a section on the line 3—3 of Fig. 1.

Fig. 4 is a section on the line 4—4 of Fig. 1.

As shown in the drawings, the tie is formed by providing two longitudinal channel members 1 which form the two sides of the tie respectively. Lattice bars 2 diagonally disposed unite the two channel members at the bottom in such a manner that the two stand in spaced relation to each other with their flanges facing. The lattice bars are riveted or otherwise suitably attached to the bottom flanges.

The two channel members are provided on the top with plates 3 which are riveted or otherwise suitably secured to the top flanges and these plates together with a hinged cover 4 constitute the top covering of the tie. The two plates 3 have their facing ends spaced apart and the cover 4 serves to cover this portion of the tie between the two facing ends of these plates. The cover is hingedly mounted to one of the channel

members 1 by means of hinges 5 and in transverse section, it is channel shaped, so that the flanges of the channel may overlie the two channel members 1. The cover 4 while being hingedly mounted to one channel member 1, when in closed position is secured against opening by means of pad lock 6 and the necessary attendant devices to permit the lock to secure the cover against opening. The space between the two channel members and below the plates 3 and cover 4 is filled with concrete or cement 7 and in this concrete are set the heads of bolts 8, the shanks of which project through the plates 3 so that they may receive the rail supporting brackets 9 which abut the rails 10 on either side, the brackets being of such conformation that they lie against the upper face of the rail flange against the rail web and against the under face of the tread.

The provision of the door or cover 4 provides for the pouring in of the concrete after the steel work of the tie has been set up and if the ballast for the tie be crushed stone, the concrete will unite therewith and when set will provide a firm mounting for the tie.

The cover 4 overlaps the adjacent ends of the two plates 3 and its flanges overhang the two channel members 1, thus serving to exclude moisture which might find its way in between the concrete and the steel channels and thereby deteriorate the latter.

The invention having been described, what is claimed as new and useful is:

A tie of the character described comprising a pair of longitudinal channel members, lattice braces uniting the channel members at their lower flanges, plates uniting the channel members on their upper flanges, the two channels being in spaced relation to each other, the two plates having their facing ends in spaced relation to each other, a cover hingedly mounted to one channel member and covering the space between the plates, means for securing the cover in closed position, a filling material in the space between the channels and below the plates and cover, and means detachably mounted upon the plates for securing railroad rails thereto.

In testimony whereof I affix my signature.

WILLIAM TOMLINSON.
